UNITED STATES PATENT OFFICE

FREDERICK J. PETERS, OF RICHMOND, INDIANA, ASSIGNOR TO THE NATIONAL AUTOMATIC TOOL COMPANY, OF RICHMOND, INDIANA, A CORPORATION OF INDIANA

DRAFTING MACHINE

Application filed December 21, 1928. Serial No. 327,630.

My improved machine is primarily designed for expediting the work of the draftsman and reducing his labor to a minimum. My leading objects are to provide a drafting machine having capacity for accomplishing a wide variety of work with increased speed without loss of precision, and provide a means for effecting accurate measurements and protractor adjustments by simple mechanical means.

Another object of my invention is to construct a precision drawing machine, adapted for inking or penciling and one that may be easily and expeditiously operated by one hand, leaving the operator's other hand free for holding memoranda, handbooks, etc., or to support himself in a more upright and comfortable position.

A further object of my invention is to keep the face of the drawing free of the usual drafting implements, such as triangles, scales, pencils, protractors, etc., by combining all of these implements into a single unit. A device of this character presents a marked improvement over the drafting machines heretofore in use in that it obviates the necessity of numerous drawing tools which usually lie all over the drawing and interfere with the acuity of the draftsman's vision.

A still further object of my invention is to so construct a machine that may be adjusted to any angle and moved to any part of the board or table without the aid of triangles, straight-edges, etc.

The characteristic features of my invention comprises a head member mounted on two sets of rollers having transverse axes, only one set of rollers being in contact with the paper at any given time. In order to bring the other set of rollers in contact with the paper, the user lightly presses a small lever which is mounted on the outside of the head. Movement of this lever causes one set of the rollers to be moved away from the

paper, while the other transversely arranged set is brought into contact therewith.

Another small lever controls the pen or pencil carrying instrumentality and which, as is also the roller shifting lever, located 50 convenient to the fingers of an operator. By varying the pressure on this lever and at the same time rolling the instrument one way or another, a dotted line or full line may be drawn as desired. The length of the line 55 may be determined in units by counting the revolutions of an indicator, which is suitably geared to the rollers, while fractions of the unit is determined by the use of a graduated dial member. As the machine is caused to 60 change its direction of movement, the pointer is automatically brought back to the zero mark and the counting started over again in order to draw a line of a predetermined 65 length in a new direction.

One of the chief objections to drafting machines of the prior type is the location of the various measuring scales. It is not an uncommon sight in a drafting room to see one or more draftsmen leaning forward considerably over their boards, and oftentimes in a standing position in order to make a particular measurement or take a reading. Straining and stretching in this manner and their consequent deleterious effects is obviated by the use of my improved type of 70 machine.

In my attempt to design a machine that will expedite the draftsman's work and at the same time conserve his energy, I have 80 mounted the indicator dial preferably at an angle with respect to the machine in order that it may be easily read two or three feet away. By providing the instrument with an inclined dial in this manner it has the further 85 advantage of enabling the user to read correctly the dial wherever the instrument is moved on the drawing without the necessity of altering his position.

Guiding means for initially maintaining 90

the instrument square with the board or paper is provided by a hinged arm, one end of which is attached to the instrument and the other end suitably braced and attached to movable trolleys translatable on a rod supported clear of the board.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an elevational view partly in section, of the head of my improved drafting machine. Fig. 2 is a view of the underside of the head showing the relation of the two sets of rollers and parts of the pointer driving mechanism. Fig. 3 is a plan view of the head better illustrating the relative positions of the actuating levers and dial. Fig. 4 is a sectional view taken substantially along line 4-4 of Fig. 3. Fig. 5 is an enlarged detail sectional view of the pointer driving mechanism. Fig. 6 is an enlarged plan view of the dial and indicator. Fig. 7 is a detail of the head holder. Fig. 8 is a detail of the translatable guide bracket used in connection with the head to hold the machine square. Fig. 9 is an enlarged detail of the manner in which the guide bracket is mounted for horizontal translation. Fig. 10 is an end view thereof. Fig. 11 is a diagrammatic assembly view of the complete machine illustrating its capability of being moved to any position on the board. Fig. 12 is a detail view of the end of the indicating pointer shaft and its actuator.

Referring now to Figs. 1 to 4 inclusive, the head unit comprises an irregular shaped housing member 15, of special contour to fit the hand. Mounted on fixed pivots within the housing 15 is a set of large wheels 16, 17, and 18, the axle 19 of the wheel 18 being mounted transversely to the axle 20 of the wheels 16 and 17.

Pivotedly mounted as at 22 between the wheel 18 and the axes of wheels 16 and 17 is a tiltable frame 21 which supports a set of smaller wheels 23, 24 and 25. As shown more clearly in Fig. 2, the small wheels 23 and 24 are journaled on one side of the pivots 22 and have their axes transverse to the axis of the wheel 25 which is also journaled in the tiltable frame 21 but on the opposite side of the pivots 22. It will be noted also that the movable wheels 23, 24

and 25 are mounted substantially at right angles to the fixed wheels 16, 17 and 18 respectively, for a purpose later to be explained.

A part 26 of the tiltable frame 21 projects upwardly into the housing 15 and is provided at its upper end with cam grooves 27 and 28 adapted to be engaged by cams 29 and 30, pinned to a shaft 31. Movement of the shaft 31 in one direction is accomplished by pressing lever 32 with the forefinger against the action of the spring 33. When the lever is released, the spring 33 rotates the shaft and cams 29 and 30 in the opposite direction. Normally, when neither of the cams 29 or 30 are in engagement with the cam grooves 27 and 28, the contacting surfaces of the two sets of wheels 16, 17, 18 and 23, 24 and 25 are all in the same horizontal plane. When the lever 32 is depressed, cam 30 engages the groove 28 and moves the lever arm 26 together with the tiltable frame 21 clockwise about the pivots 22. This movement of the carriage 21, elevates the wheels 23 and 24 and lowers the wheel 25. The lowering of the wheel 25 forces the larger wheel 18 away from the surface on which the machine is placed and only those wheels having parallel axes are in contact with the paper thus permitting the machine to be rolled toward the right or left.

The releasing of the lever 32 causes the reverse to happen. The frame 21 is moved anti-clockwise about the pivots 22, wheels 22 and 23 are lowered into contact with the surface while the large wheels 16 and 17 are forced away, wheel 25 is elevated slightly allowing wheel 18 to come into contact with the surface to permit the machine to be moved in a direction at right angles to the first mentioned movement. In order to clarify somewhat the above movements it may be well to divide further the two sets of wheels 16, 17, 18 and 23, 24 and 25, into an additional classification i. e. those having parallel axis for left and right movement (wheels 16, 17 and 25) and those having parallel axes for movements toward or away from the operator (wheels 18, 23 and 24). Each of these last mentioned classes comprises at least one large wheel journaled on fixed centers for a purpose now to become apparent.

It is one of the objects of my invention to provide a drawing machine with an easily readable and accurate measuring instrumentality, and to this end, I have secured to the axle 20 and rotatable therewith, a bevel gear 34 which is constantly in mesh with a similar gear 35 mounted on the axle 19. In mesh with the gear 35 and inclined at an angle I have mounted the gear 36 which drives the pointer 37. Thus it will be seen that whether the wheel 18 or the wheels 16

and 17 are in contact with the paper, the pointer 37 will be caused to rotate about the graduated dial 38. The direction of rotation however, is dependent upon the direction in which the machine is moved.

The driving mechanism for the pointer 37 consists of a sleeve 39, formed integral with the gear 36, in which is mounted the tapered thimble 40. A coil spring 41 acting through the headed pin 42, presses against a leaf spring 43 and draws the tapered thimble 40 into engagement with the tapered bushing 44. When the parts are in the position shown in Fig. 5, the pointer 37, being connected to the thimble 40 as by means of a shaft 45 and pin 46, is caused to rotate with the gear 36. Assuming that the operator has drawn a line of a predetermined length and wishes to draw another perpendicular thereto, all that is required to be done is to press or release, as the case may be, the lever 32 which automatically throws the pointer 37 to the zero position and engages with the paper a different set of wheels as previously described.

When the lever 32 is pressed a third cam 47 mounted on the shaft 31 engages the end of the leaf spring 43 causing it to move about its fulcrum 48 and force upwardly on the non-rotatable pin 42. One end of the pin 42 is slidably secured to the leaf spring 43 and the other end is formed with an enlarged beveled head 49 and as the pin is moved upwardly the beveled surfaces on the head 49 engage the concavely beveled surfaces 50 formed on the shaft 45. The initial translatory movement of the shaft 42 releases the pressure which holds the tapered thimble 40 in its tapered seat in the bushing 44, a further axial movement of the shaft 42 brings the non-rotatable beveled surfaces 49 into engagement with the now freely movable surfaces 50 and by the camming action thus effected, rotates the thimble 40 and shaft 45 sufficiently to bring the pointer 37 to its zero position on the dial. Fig. 12 is an enlarged view of a portion of the rotatable pointer shaft 45 and its actuator. The line 50^a indicates a valley formed between the inclined side walls 50, portions of which, at either side of a line perpendicular to the valley line, are cut away on an angle as shown, thereby forming the flats 50^a and inclined ridges 50^b. Thus, irrespective of the position of the pointer 37, the wedge-like head 49, when brought into engagement with the inclined faces 50 or ridges 50^b of the pointer shaft, will turn the pointer to a zero mark. The ridges and valleys of the cooperating members are so arranged with respect to the indicia on the dial that when the faces 49 and 50 are fully engaged, the pointer registers zero. At this point the cam 47 slips over the end of the leaf spring 43 which permits the spring 41 to draw the

pin 42 and the tapered thimble back into its seat which again locks the pointer to the gear 36.

Another object of my invention is to construct a drawing machine provided with a lead carrying instrument which will require the least amount of attention on the part of the user. In accomplishing this objective I have designed the pencil or lead carrier preferably in the manner illustrated in Fig. 7. The lead or pencil 51 is held in an inclined sleeve member 52 by means of the spring clip 53 partially surrounding the sleeve and held in slots 54. The spring clip exerts a slight pressure on the lead 51 and thus prevents the latter from falling out. The outward advance of the lead is controlled by a steeply pitched screw 55 threaded to the bore 56 of the sleeve 52. A slight turning of the screw 55, it will be seen, advances the lead considerably.

In order to make the lead self sharpening, I have mounted the sleeve on centers 57 and 58 whereby the sleeve 52, lead 51, and screw 55 are permitted to rotate about their longitudinal axes. Inclining the carrier at an angle as shown in Fig. 1, causes more or less friction on one side of the center of the lead 51 and as the machine is moved along this unbalanced friction causes the lead 51 slowly to creep around and in this way the point of the lead is automatically maintained in a sharpened condition. Means to vary the tension on the barrel or sleeve 52 and to permit ready assembling of the parts is provided by an adjustable bushing 59 mounted on the bracket 60.

The weight of the line to be drawn is controlled by a small lever 61, pivoted at 62 and having an arm 63 engaging the bracket 60 of the holder. As shown in Fig. 1, one end of the bracket 60 is pivotally attached to the machine at one of the pivots 22 and it becomes apparent that varied pressures on the lever 61 will cause a full line or dotted line to be drawn as desired. The foregoing is merely representative of a preferred type of pencil holder which may be used to advantage. However, any other means for holding a pencil or a pen may be substituted therefor without departing from the spirit of the invention.

It becomes important in expediting the work of the draftsman, to maintain the machine at all times square with the board and therefore, I have secured the former at 64 to a jointed yoke member 65 slidably mounted for horizontal movement on a rail 66 located preferably above the drawing board. Each end 65' and 65'' of the yoke member 65 is pivotally secured to a strap 67, (only one of which is shown on the drawings) which is guided along the rail 66 by means of wheels 68, 68' and 69.

The yoke member 65 is broken as shown

at 70 to permit the machine to be moved toward or away from the operator while the trolleys 71 permit of a left or right movement. Thus it will be apparent that the machine may be moved to any part of the drawing board and at the same time be held square with a predetermined line.

There are occasions, however, when it becomes necessary to draw a line at an angle with respect to the above mentioned movements and this is accomplished in the following manner.

The yoke member 65 is secured at 64 to a pivotally mounted protractor arm 72 which is held in position on the graduated scale by a spring member 73 engaging a slot 74 formed on the inner periphery of the scale 77. A series of slots 74 may be formed as indicated in Fig. 3 for the most often used angles. As shown in the drawings the machine is positioned at right angles to the yoke member 65 but by pressing the spring 73 out of one notch and by turning the machine about the pivot 75 until the spring snaps into any other notch, a line may be drawn at the desired angle. To obtain angles which are between the notches 74, the clamp nut and bolt 76 is tightened which tightly holds the arm 72 in any desired position about the fixed scale 77.

The operation of the machine is as follows: the operator grasps the machine with one hand, putting his thumb in the indentation 78 formed on the side of the housing 15, his forefinger on lever 32, and his middle finger on lever 61, moves the machine to the point where he wishes to start a line and sets the pointer 37 to the zero mark. To draw a line to the right 5 inches long, for example, he would press lever 32 all the way, press lever 61 slightly and roll the machine to the right until the indicator made, in the present case, $1\frac{1}{4}$ revolutions and then stop. To draw a 5" line perpendicular to the one just drawn, the operator releases lever 32 all the way (which automatically returns the pointer to zero and engages the paper with the other set of wheels) and moves the machine toward or away from him until the pointer registers $1\frac{1}{4}$ revolutions which indicates that a line 5 inches long has been drawn, and so on until he finishes his drawing.

In the machine illustrated, the ratio between the circumference of the dial 38 and the circumference of the wheels 16, 17 and 18 is the same, i. e. one revolution of the large wheels equals one complete revolution of the pointer 37, but this ratio need not be the same in all cases as it is obvious that by changing the diameter of the large wheels or varying the ratio between the pointer driving gears an entirely different pointer travel may be obtained which, for certain classes of work, may be found to

be highly desirable when used in conjunction with a differently graduated dial.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of United States:—

1. A drawing instrument adapted to be used on a drawing board combining marking instrumentality; a casing member; traction wheels journaled on transverse axes in said casing and having a portion of their periphery extending below the casing to engage the drawing board; a tiltable frame member pivoted in said casing; a second set of traction wheels, having their axes transversely arranged, journaled in said frame and having portions of their periphery projecting from said casing, certain of the said two sets of wheels being arranged on parallel axes; a lever; and means actuated by the movement of said lever to tilt said frame to bring only those wheels having parallel axes into contact with the drawing board.

2. A drafting machine for use upon a drawing board combining a movable casing member; a drawing instrumentality carried thereby and means mounting said instrumentality whereby it may be brought into contact with the drawing surface; a plurality of rollers having mutually normal axes journaled in said casing; an indicator casing; a pointer in said casing; driving mechanism for said pointer operable in timed relation with the movement of one of said rollers; means to disengage said pointer from said driving mechanism; and a yoke member connected to said casing and adapted normally to hold the latter in a predetermined angular position relatively thereto.

3. A drawing machine combining a casing member; a tiltable frame member journaled therein; a plurality of sets of rollers journaled in said members the axes of each set being arranged transversely to the axes of the other set; a marking instrumentality carried by said casing member; means mounting said instrumentality whereby it may be brought into contact with the drawing surface; an indicator carried by said casing; driving mechanism for said indicator; means for selectively tilting said frame

thereby to render effective either of said sets of rollers; and means controlled by said frame tilting means to disengage said pointer driving mechanism.

5 4. A drafting machine combining, a movable casing member; a tilttable frame member pivoted therein; a plurality of traction wheels journaled in said casing on opposite sides of the axis of said tilttable frame; a second group of traction wheels journaled in said tilttable frame on opposites of its axis; means for tilting said frame thereby to engage a drawing surface with traction wheels of each group; a marking instrumentality; movable with the casing member; an indicator device on the casing member for indicating the amount of movement of the machine relative to the drawing surface; means actuated by one of said traction 15 wheels to actuate said indicator; and means controlled by said frame tilting mechanism to render the indicator actuating means ineffective.

5. A drawing instrument for use on a drawing board combining a casing member; two sets of relatively adjustable traction wheels one set being journaled in said casing; means mounting the other set in said casing, the axis of one set of wheels being transverse 20 to the axis of the other set; means for effecting a relative substantially vertical adjustment between said two sets of wheels selectively to engage the drawing board with either set; a drawing instrumentality carried 25 by said casing; and means for guiding said casing; said means including a trammel bar, and a yoke member slidably mounted on said bar and having one end secured to said casing member.

40 6. A drawing machine combining a casing member; a frame pivoted thereto; a group of traction wheels journaled in said casing on opposite sides of the pivotal axis of said frame; a second group of traction wheels 45 journaled in said frame; means selectively to tilt said frame relative to said casing to engage one wheel of each set with a drawing surface; a marking instrumentality movable with said casing; an indicating device on the casing member actuated in timed 50 relation with the rotation of one of the traction wheels of each group for indicating the amount of movement of the machine relative to the drawing surface; and means actuated 55 by said frame tilting means to control said indicating device.

7. A precision drawing instrument combining a housing member; a group of traction wheels journaled therein and having 60 their axes arranged perpendicular to each other; a movable frame member pivoted in said housing; a second group of traction wheels journaled in said frame and having their axes arranged perpendicular to the 65 axes of said first mentioned wheels; means

to effect a relative tilting movement between said housing and said frame whereby selected wheels of both of said sets are moved into contact with the drawing surface all of the wheels in contact with the drawing 70 surface having parallel axes; an indicator pointer carried by said housing member and operatively connected to one of said wheels; and means controlled by said frame tilting means to control the movements of said 75 pointer.

8. A drafting machine combining, a movable head member; a drawing instrumentality carried thereby; two sets of traction rollers adjustably journaled in said head the 80 axes of the rollers of each set being parallel, the axes of one of said sets of rollers being arranged transversely to the axes of the other set; and means selectively to engage either of said sets of rollers with the surface 85 upon which the machine is placed.

9. A drafting machine combining, a head member movable over a paper in a predetermined path; a marking instrumentality which wears in use carried by said head 90 member; a support for said marking instrumentality, said support comprising a holder rotatably journaled in said head member and arranged oblique to the surface of the paper and oblique to the path of movement 95 of said head member, whereby contact between the paper and said marking instrumentality, as said head member is moved, will cause rotation of said support and marking instrumentality thereby to sharpen 100 said instrumentality.

10. A drawing machine combining a casing member; a frame member mounted therein and movable relative thereto; a first group of traction rollers journaled in said 105 casing and having their axes perpendicularly arranged to each other; a second group of traction rollers journaled in said frame and arranged with their axes respectively parallel to the axes of said first group; a marking instrumentality carried by said casing; means for actuating said marking instrumentality to cause a mark to be made thereby; and means selectively to engage the drawing surface with sets of rollers having 110 mutually parallel axes.

11. A drawing machine combining a casing member; a frame member pivotally mounted in said casing; a first group of rollers mounted in said casing; a second group of rollers mounted on said frame and having their axes transversely arranged to axes of said first mentioned group of rollers; selective means to move either of said groups of rollers into contact with the drawing surface, the rollers of each group having parallel axes; a marking instrumentality mounted in said casing; and means to render said marking instrumentality effective.

12. A drafting machine combining a movable casing member; a drawing instrumentality carried thereby; a plurality of sets of rollers journaled in said casing and having their axes transversely arranged, the axes of the rollers in each set being parallel; and means for selectively engaging one of said sets of rollers with the drawing surface.

13. In witness whereof, I have hereunto subscribed my name.

FREBERT J. PETERS.
